CARTRIDGE FOR BLASTING

James Taylor and William Young, Saltcoats,
Scotland, assignors to Imperial Chemical Industries Limited, a corporation of Great Britain

Application February 18, 1935, Serial No. 7,083
In Great Britain February 20, 1934

4 Claims. (Cl. 102—10)

This invention relates to blasting devices of the kind comprising a charge adapted, on initiation, to generate gas, and a pressure resistant metal vessel containing the said charge together with suitable initiating means, the said vessel being adapted to release the generated gases at a sufficient pressure to cause a blasting effect in the borehole. The gas release means preferably consists of a rupturable and replaceable bursting disc, but may also take the form of a suitably adjusted valve.

More particularly the invention relates to an improved device of the above character which is applicable for use in fiery mines or in mines where a large yield of lump coal is desired.

In the particular forms of device with which the present invention is concerned there are provided two rigid containers which are screwed together before use, one of these containers being charged with a non-detonating explosive and being provided with a means for igniting it, the other container being wholly or partly filled with a liquid, the two being separated, when the device is assembled, by a water-proof disc adapted to withstand only very low pressures. A device of this character is described in the specification of our pending application Serial No. 712,051.

According to the above specification there was employed a quantity of a solution or suspension of a quantity of exothermically reacting gas evolving material together with heating means inadequate in themselves to determine the venting of the contents from the device, a charge of a non-detonating explosive as heating means being included in one compartment of a device of the kind described, and a charge of a solution or suspension of the exothermically reacting gas evolving material being included in the other compartment. The quantities of the charges were so arranged that the venting of the apparatus as a whole would not take place when the liquid was replaced by an equal quantity of water.

It is also possible, however, to achieve a blast advantageously in an apparatus of the character described, without the use of the exothermically gas evolving liquid, and according to the present invention water is used in an apparatus of the above character for the purpose of quenching and/or cooling the products of combustion of the non-detonating explosive contained in the first compartment provided the charge of non-detonating explosive in the first compartment is sufficient to cause venting as the result of pressure built up in the free space available for its combustion. Besides cooling the combustion

products within the apparatus, the cooling and quenching effect of the water persists after the venting, and sufficient is used to fill a substantial portion of the second compartment, so that the desirable quenching effect may be obtained. Besides cooling the combustion products the water has a hydraulic effect which is effective in blasting. The quantity of the non-detonating explosive required for the first compartment will in general be greater than that which is employed as the heating medium when an exothermic gas producing liquid is employed, but can best be determined by trial and error, it being advantageous to use at least from 12-25% more than the minimum amount.

The device is charged and assembled shortly before use and is loaded into the borehole as a whole. The two containers and the cap are made strong enough to withstand the force of the explosion and can be recovered and used repeatedly.

One form of our invention is illustrated in the attached drawing, which represents a central longitudinal section of the device.

A rigid steel container 1 is closed at one end by a screw-in plug 2 through which passes an insulated electrode 3 which is so constructed as to be gas-tight at pressures up to 25 tons per sq. in. Near the other end of the container is provided a shoulder 6 against which rests a fibre waterproof disc 5. The disc is held firmly in place by means of a second container 4 which screws into the open end of the first container. The disc serves to close the passage between containers 1 and 4, but is not strong enough to withstand any but very low pressures. The other end of container 4 is provided with a shoulder 7 and a steel bursting disc 8. A fibre sealing washer 12, is interposed between the disc 8 and the shoulder 7. The bursting disc is held firmly in position by means of the hollow screw-in cap 9 which is pierced by one or more channels 10 through which the blasting force is directed and distributed. The terminals 13 and 14 of the electrodes are covered by a screwed on cap 15 provided with an aperture 16 for the insulated leads from the exploder or other suitable source of current.

The container 1 is loaded with a charge of a non-detonating explosive which is ignited by means of an appropriate fuse 17, one lead of which is connected to the electrode 3 and the circuit is completed via the metal container by the electrode 11. As suitable explosives we may mention blackpowder, N. D. cordite flake, and mixtures containing charcoal and ammonium ni-

trate. If desired this may be made up in cartridge form with or without the igniter. Container 4 is wholly or partly filled with water.

When the device is fired, the charge 18 in container 1 begins to burn, bursting the disc 5. The combustion products are then cooled progressively by the water 19 in container 4 and by expansion, so that by the time the bursting disc 8 has burst and the water has been ejected they are incapable of igniting firedamp or coal dust. The duration and degree of cooling may be regulated by choosing a powder with a suitable rate of burning and by selecting a sealing disc adapted to burst at an appropriate pressure. Besides cooling the combustion products the water exerts a hydraulic effect which is effective in blasting. The cartridge is loaded into the borehole with the cap 9 inmost. If desired it may be tamped.

The weight of the charge will depend on the size of the device used. A device of the example illustrated, with a powder chamber of 230 c.c. capacity, is loaded with 90 gm. cordite in flake form and a 5 grain powder fuse connected electrically to the electrodes. The water chamber 25 of capacity 440 c.c. is completely filled with water and the cartridge is screwed up. The cartridge so prepared will not ignite to a 9% methane-air mixture when fired in it.

We claim:

1. A blasting device comprising a pressure-resistant container, means for venting the gases radially from the container at a predetermined and considerable pressure, means for initiating the decomposition of a non-detonating, gas-generating explosive composition contained therein, and a pressure-responsive waterproof means separating said container into two compartments, the compartment adjacent to said venting means containing water in an amount sufficient to cool 1 and quench the products of combustion of said explosive charge, and the other said compartment containing a non-detonating explosive, said means for initiating the decomposition of said explosive and a volume of compressible gas 1 sufficient to cause the commingling between the products of combustion of the explosive and the water in the adjacent compartment before said venting means is actuated.

2. The blasting device of claim 1, in which 2 said non-detonating explosive comprises black powder.

3. The blasting device of claim 1, in which said non-detonating explosive comprises ammonium nitrate and charcoal.

4. The blasting device of claim 1, in which said non-detonating explosive comprises cordite.
